US0D1059361S

(12) **United States Design Patent** (10) **Patent No.:** **US D1,059,361 S**
(45) **Date of Patent:** **** Jan. 28, 2025**

(54) **DISPLAY MODULE**

(71) Applicant: **Samsung Display Co., Ltd.**, Yongin-si (KR)

(72) Inventors: **Yong-Woo Koo**, Asan-si (KR); **Kee Hyun Nam**, Seoul (KR); **Jun-Woo Kim**, Seoul (KR); **In-Young Cho**, Busan (KR)

(73) Assignee: **Samsung Display Co., Ltd.**, Yongin-si (KR)

(**) Term: **15 Years**

(21) Appl. No.: **29/794,100**

(22) Filed: **Jun. 10, 2021**

(30) **Foreign Application Priority Data**

Dec. 11, 2020 (KR) 30-2020-0061474

(51) **LOC (15) Cl.** **14-02**

(52) **U.S. Cl.**

USPC **D14/432**; D14/248

(58) **Field of Classification Search**

USPC ..... D14/138 R, 138 AA, 138 C, 138 G, D14/140.11, 203.1, 203.3, 203.7, 214, D14/217, 248, 250, 289, 348, 371, 374, D14/405, 424, 432, 439, 464, 501-502, D14/505, 435-436; D21/324-325, 329, D21/332; D13/162, 184, 154, 182

CPC C09J 7/00; C09J 7/29; C09J 2201/122; G06F 1/1626; H04B 1/3888; G02F 1/133308; G02F 2001/133314; G02F 1/133512; H04N 5/2257

(57) **CLAIM**

The ornamental design for a display module, as shown and described.

DESCRIPTION

FIG. 1 is a front perspective view of the display module; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the broken lines illustrate portions of the display module that form no part of the claimed design.
